UNITED STATES PATENT OFFICE

2,637,527

WELL DRILLING DEVICE

Joseph B. Andrews, Jr., Cincinnati, Ohio

Application August 21, 1950, Serial No. 180,655

4 Claims. (Cl. 255—4.8)

1

The present invention relates to improvements in well drilling apparatus, and more particularly to the means for supporting the well drilling apparatus within a well hole without the use of well casings.

An object of the present invention is to provide an improved well drilling apparatus that is adapted to be engaged with the inner surface of a well hole, with means being provided for varying the vertical angularity of the drill shaft.

A further object of the present invention is to provide an improved arrangement for supplying rotary movement to the drill shaft, novel means also being provided for vertically moving the drill shaft.

Yet another object of the present invention is to provide a novel fluid actuated means for positioning the well drilling apparatus within a well hole.

A further object of the present invention is to provide a novel indicating means for association with the well drilling apparatus whereby the angularity of the well drilling apparatus with respect to the vertical may be ascertained, other means being provided for correcting the positioning of the drill shaft.

Various other objects and advantages will be apparent from the detailed description to follow. In the description as well as in the claims, parts are at times identified by specific names for convenience, but such nomenclature is intended to be as generic in its application to analogous parts as the prior art will permit. My invention is illustrated in the accompanying drawings, wherein:

Figure 1 is a vertical plan view of the structure of the present invention positioned within a well hole with an indicator positioned above the well hole;

Figure 2 is a horizontal transverse sectional view taken substantially along the plane of line 2—2 of Figure 1;

Figure 3 is a vertical transverse sectional view taken substantially along the plane of line 3—3 in Figure 2;

Figure 4 is a horizontal transverse sectional view taken substantially along the plane of line 4—4 of Figure 3;

Figure 5 is a detail sectional view through the indicating means of the present invention; and

Figure 6 is a horizontal transverse sectional view taken substantially along the plane of line 6—6 of Figure 5.

Referring more particularly to the drawings, wherein like numerals designate like parts throughout, the numeral 10 designates generally

2

the tubular housing, the numeral 12 designates generally the drill means rotatably disposed in the housing 10, the numeral 14 designates generally the means for rotating the drill means, the numeral 16 designates generally the means for vertically moving the drill means, the numeral 18 designates generally the means for supporting the housing within a well hole, the numeral 20 designates generally the adjusting means for adjusting the positioning of the housing with respect to the vertical, and numeral 22 designates generally the indicating means of the present invention.

The tubular housing 10 is comprised of a substantially tubular member 24 having a partition wall 26 disposed intermediate its ends, a cap closure 28 threadably mounted on its upper end, and a drill shaft bearing member 30 closing its lower end. The tubular housing 10 is supported by the eyelet 32, ring 34, and supporting cable 36. The eyelet 32 may be either threaded into the cap 28 or welded as shown.

The well drill means 12 of the present invention is comprised of a substantially tubular shaft 38 which is reciprocably and rotatably mounted within the opening 40 in the shaft bearing member 30 and has its upper end rotatably disposed in the bearing threadably secured to the piston head 44. The piston head 44 is recessed at 46 for receiving the annular flanged end 48 of the tubular shaft 38. The inner race 50 of the ball bearing unit 42 is press fitted on the tubular shaft 38 for rotatably supporting the same, the inner race 50 acting as a thrust bearing also. The lower end of the tubular shaft 38 is provided with a tapered exteriorly threaded reduced portion 52 which is threadably received within the drill member 54 which is the upper end of the drill head, indicated generally at 56.

A drilling fluid supply conduit 58 is connected to the housing 10 at the conduit connection 60, and the conduit 62 within the housing 10 is in communication with the conduit 58 terminating at its other end within the tubular shaft 38 whereby the drilling fluid may be supplied to the drill end of the drill shaft. An intermediate portion of the conduit 62 is mounted within the partition wall 26 and held from movement thereby at 64. The substantially rigid portion of the conduit at 66 is disposed through the piston head 44, a stuffing box 68 being provided in the piston head 44 so that reciprocation of the piston head 44 on the conduit 66 will be accompanied by sealing engagement with the conduit 66.

The means for rotating the drill shaft 38 in-

cludes a spur gear 70 which is fixedly mounted on the exterior of the tubular shaft 38. An electric motor 72 is secured to the piston head 44 by the sprocket and bolts at 74. The electric motor shaft 76 has mounted thereon the gear 78 which is operatively associated with the spur gear 70 for effecting rotation thereof. The means for supplying electrical power to the electric motor 72 includes the conduit 80 which extends from the surface of the earth downwardly, terminating at 82 in the housing 10. As seen best in Figures 3 and 4, it will be seen that the tubular housing 10 is provided with a longitudinally extending recess 84 in which are mounted a pair of contact bars 86 and 88 which are insulated from each other by the insulating mounting material 90 within the recess 84. It will readily be seen that movement of the piston head 44 downwardly, accompanied by movement of the electric motor 72, will not interfere with the completion of the electric circuit, since contact points 92 and 94 extending from the motor 72 are always in contact with the vertically extending bars 86 and 88 for supplying power to the motor.

The means for vertically moving the well drill shaft 38 includes the piston head 44 which is reciprocably mounted within the tubular housing 10 and is provided with sealing rings 96 for engagement with the inner surface of the tubular housing 10. A fluid pressure supply conduit 98 terminates at the connector 100 disposed in the cap 28 on the housing 10, and a substantially rigid conduit 102 extends from the connector 100 to the partition wall 26, whereby fluid may be supplied within the chamber 104 above the piston 44 for effecting downward movement of the piston head 44, which will, of necessity, be accompanied by downward movement of the drill shaft 38.

The means for supporting the housing within the well hole H includes a plurality of longitudinally extending surface-engaging members 106, 108, 110 and 112 which are provided with upwardly turned ends 114. Each of these wall engaging members is provided with inwardly extending piston rods 116 which are reciprocably disposed within the piston cylinders 118 which are threadably mounted within the housing 10. A pair of the cylinders 118 are provided for each wall engaging member and are disposed adjacent the upper and lower ends thereof. A main fluid conduit supply 122 is comprised of a plurality of individual supply conduits designated generally at 124 which are adapted to be individually connected to the piston cylinders 118 on the back side of the piston rods 116, whereby fluid pressure supplied to the cylinders will effect outward movement of the wall engaging members 106 through 112. It should be noted that when the pressure is relieved from the conduits 124 the entire mechanism may be lifted from the well hole, since the well engaging members will not be pressed against the inner surface of the well hole.

As seen best in Figure 5, the indicating means of the present invention includes a casing 126 which is of cup shape and has an upper closure cover 128 threadably mounted thereon, with screws 130 adapted to be threaded into the cap 28 of the housing 10 for mounting of the casing 126. A ball socket 132 is centrally disposed within the cover 128 and has swingably mounted therein the pendulum 134. An electrical conductor 136 is connected to the upper end of the pendulum 134 and passes through a bushing 138 in the casing 126 and a bushing 139 in the tubular hous-

ing 24, passing upwardly to the surface of the ground to the indicator at 140. Secured within the casing 126 is the curved plate 142 having a plurality of spaced contact points 144. Each of the contact points 144 is provided with an individual conductor 146 which are assembled into a single conduit 148 passing to the surface of the ground for connection to the indicator 140. It will readily be seen that when the housing 10 of the well drilling means of the present invention is disposed within the well hole H, the relationship between the housing 10 and the vertical will be indicated by means of the contact between the pendulum 134 and one of the contact points 144 which will complete a circuit and disclose to an observer on the surface, by means of the indicator 140, the angularity of the housing. A second indicating means, indicated generally at 150, may be mounted at the lower end of the housing 10 on the member 30 for cooperation with the upper indicating means.

From the foregoing description, taken in conjunction with the drawings, it is believed that one skilled in the art will readily understand the operation, and further detailed description at this point is deemed unnecessary. When the housing 10 has been lowered into the well hole H, fluid pressure is applied to the cylinders 118, causing the wall engaging members to engage with the surface of the interior of the well hole, securing the housing 10 within the hole. An examination of the indicator at 140, combined with operation of control valves for the supply conduit 124, will permit adjustment of the housing 10 until the desired degree of correct positioning of the housing is accomplished. The drill shaft may then be lowered to ground engaging position and the electric motor 72 may then be actuated for drilling while the fluid supply conduit 58 supplies drilling fluid to the drill head.

Some changes may be made in the construction and arrangement of the parts of my device without departing from the real spirit and purpose of my invention, and it is my intention to cover by my claims any modified forms or structure or use of mechanical equivalents which may be reasonably included within their scope without sacrificing any of the advantages thereof.

Having described the invention, what is claimed as new is:

1. A well digging device comprising a tubular housing closed at its upper end and having a drill shaft bearing bore at its lower end, a drill shaft rotatably disposed in said housing and downwardly movable through said bore, a motor enclosed in said housing at one side of said shaft and operatively connected thereto for rotating said shaft, means for moving said shaft and said motor downwardly, and remote control fluid pressure responsive means for supporting said housing within a well hole, and adjusting the housing with respect to the vertical.

2. A well digging device comprising a tubular housing closed at its upper end and having a drill shaft bearing bore at its lower end, a drill shaft rotatably disposed in said housing and movable downwardly through said bore, first means for rotating said shaft, and second means for moving said shaft downwardly, said first means including an electric motor enclosed in said housing at one side of said shaft and movable downwardly in said housing by said second means, electric supply means for said motor including conducting wires terminating in said housing, a pair of vertically disposed conducting bars fixed in said

housing and connected to said wires, said motor having means slidably engaging said bars and completing a circuit with said bars to said motor.

3. A well drilling device comprising a tubular housing closed at its upper end, a piston working in said housing, a hollow drill shaft rotatably suspended from said piston for downward movement thereby during rotation thereof, a motor enclosed in said housing and suspended by an upper end thereof from said piston at one side of the shaft with gearing between its lower end and the shaft for downward movement by said piston with said shaft to rotate the shaft during downward movement of the shaft, means for introducing hydraulic pressure into said housing above said piston to move the same downwardly, means for introducing drilling liquid into said shaft during downward movement and rotation thereof, and means for supporting the housing in a well hole.

4. A well drilling device according to claim 3,

said last means including a conduit fixed to the upper end of said housing and slidably extending through said piston into said shaft.

JOSEPH B. ANDREWS, JR.
